his Attorney

UNITED STATES PATENT OFFICE.

EDSON R. WOLCOTT, OF LOS ANGELES, CALIFORNIA.

PENCIL SHARPENER.

1,418,858.

Specification of Letters Patent. Patented June 6, 1922.

Application filed November 3, 1919. Serial No. 335,349.

To all whom it may concern:

Be it known that I, EDSON R. WOLCOTT, a citizen of the United States, residing at Los Angeles, in the county of Los Angeles 5 and State of California, have invented a new and useful Pencil Sharpener, of which the following is a specification.

This invention relates to a device for sharpening pencils, and particularly to a 10 sharpening device which is adapted to be attached to a pencil so as to remain thereon while the pencil is in use, and permit sharpening of the pencil at any time without having to take the time for applying and removing the sharpener.

The accompanying drawings illustrate embodiments of my invention, and referring thereto:

Fig. 1 is a rear end view of a form of the 20 device made in one piece;

Fig. 2 is a vertical section thereof;

Fig. 3 is a side elevation of a form of the 25 invention provided with removable cutting blades or dies;

Fig. 4 is a section on line 4—4 in Fig. 3;

Fig. 5 is a side elevation of one of the cutting blades or dies.

The form of the invention shown in Figs. 1 and 2 comprises a cylindrical body 1 adapted to fit on a pencil and having a conical extension 2 provided with cutting dies 3 and with slots 4 for discharge of the cuttings. Dies 3 are preferably serrated, as shown at 30 6, to enable them to more readily cut away the wood of the pencil, such serrations being preferably formed in the manner of screw threads analogous to screw cutting dies, and said dies preferably terminate in 35 knife portions or blades 5 adapted to trim the pencil point to the required degree of 40 fineness, said knife portions being separated sufficiently to enable the pencil point to project between and beyond them.

In using the device, the body 1 is slipped 45 over one end of the pencil and the device then turned and pressed against the pencil end to cause the same to be cut conically to form the pencil point and sharpen the pencil. When the pencil has been sharpened in 50 this manner, the device may be left in po-

sition, the pencil point protruding sufficiently from the device to permit use of the pencil; and when re-sharpening of the pencil is required the same can be effected by simply turning the device in contact with the pencil until the latter is cut away to the required extent. The pitch or screw thread character of the cutting serrations 6 tends to force the device onto the pencil as it is turned therein, and thereby facilitates the 60 sharpening of the pencil, and the serrations also tend to hold the device in position on the pencil, while allowing its ready withdrawal when desired by turning it in the opposite direction.

The cutting blades or dies may be made 65 detachable to enable replacement thereof, if desired. Thus, as shown in Figs. 3 to 5, the body 7 of the device, which is tubular and cylindrical to fit on the pencil, may 70 have sockets 8 which are undercut to engage and grip the dies 9, said dies engaging at their outer ends in similar sockets 10 in a ring 11. The dies in this case may be of similar construction to the die portions 75 shown in Figs. 1 and 2, and may be similarly provided with terminal cutting knife portions, indicated at 12, and the operation of the device is the same as above described.

What I claim is:

1. A pencil sharpener comprising a tubular body portion having conically extending cutting portions at one end thereof and adapted to cut the end of the pencil to conical shape, and said cutting portions having 85 knife extensions adapted to cut the extreme point of the pencil and separated to permit the pencil point to project between and beyond the same.

2. A pencil sharpener, as set forth in 90 claim 1, wherein said cutting portions are formed with screw threads adapted to engage the cut portion of the pencil to force and hold the sharpener onto the pencil.

3. A pencil sharpener comprising a tubular body adapted to fit on the pencil and provided with conically extending cutters adapted to cut the end of the pencil, said 95 conically extending cutters having pointed serrations adapted to cut into the wood of 100

the pencil so as to retain the sharpener in place on the pencil, and with cutting means extending beyond said conically extending cutters in position to sharpen the lead of the pencil.

4. A pencil sharpener comprising a tubular body adapted to fit on the pencil and

provided with conically extending cutting portions formed as screw threads adapted to force and hold the sharpener onto the pencil. 10

In testimony whereof I have hereunto subscribed my name this 25th day of October, 1919.

EDSON R. WOLCOTT.
